Primary Examiner — Philip S Hyder*Assistant Examiner* — Ryan Harvey(74) *Attorney, Agent, or Firm* — Womble Bond Dickinson (US) LLP(57) **CLAIM**

The ornamental design for a stepper exercise machine, as shown and described.

DESCRIPTION

FIG. 1 is a perspective view showing the new design for a stepper exercise machine.

FIG. 2 is a left view thereof;

FIG. 3 is a right view thereof;

FIG. 4 is a front view thereof;

FIG. 5 is a rear view thereof;

FIG. 6 is a top view thereof; and,

FIG. 7 is a bottom view thereof.

The broken lines, if there are any, showing of portions of the stepper exercise machine depict environment and form no part of the claim.

1 Claim, 7 Drawing Sheets(56)
